BOILER CONTROL

Hubert S. Turner, New York, N. Y.

Original application June 24, 1936, Serial No. 86,999. Divided and this application January 7, 1938, Serial No. 183,854

4 Claims. (Cl. 122—504)

My invention relates to improvements in heating systems wherein a boiler is employed for generating the heating medium such as steam, and more particularly has reference to and is illustrated in the accompanying drawing in its application to a steam boiler, the object being to prevent operation of the boiler without a predetermined level of water therein and this application is a division of my pending application S. N. 86,999 filed June 24, 1936 and now Patent No. 2,169,077.

When an automatic heater is used, such as an oil fueled steam or hot water boiler, the water gauge is not always kept under observation the same as with manually fueled boilers, and many oil burners are not provided with cut-offs which automatically operate when the water becomes low. To overcome this, I have devised a control which will prevent operation of the boiler when a predetermined low water level is reached.

In the accompanying drawing I have illustrated a suitable form of apparatus in perspective embodying an application of my invention, parts being broken away.

41 and 42 indicate two small bellows attached to a header 43 and frame 43' having pivot 107. Air outlet pipe 44 is connected with bellows 41, and on each side of the header 43, extending parallel with bellows 41 and 42, is a bifurcated bar 46, 46' connected across at the right end by yoke 46'' as shown. Between said bellows is coiled spring 47, adjustable by the nut 48, which threadably engages the bar 48' within tube 48'' passing through chamber 43, and said bar 48' is attached to one end of said spring and the opposite end of said spring 47 is secured to cable 51. Nuts 49 control the movement of the roller 50 in the slots 50'' in bar 46, 46', and the flexible cord or chain 51, passes over roller 50 to its anchorage at 51' on the frame 43' as shown.

The water in the boiler also circulates in header 43, being supplied through tube 45 and bellows 42 which are below the water level in the boiler, and as the water in the boiler approaches low water level, the water in header 43 being parallel therewith and fed therefrom, and being relieved of the weight of some of the water in said header, is forced upwardly by the action of spring 47 pulling on cord 51, passing over roller 50, and anchored at 51'. Due to the leverage exerted by the projecting bar 46, 46', pivoted on stud 107, and corresponding stud on the other side, the header 43 rises, and the left end thereof comes in contact with the lower side of the horizontal arm 23' of angle 23, forcing the latter to the left,

tripping piece 20 normally resting on lug 22, shutting off the burner, the mercury contact tube 19 falling and breaking the circuit to the oil burner motor or other appliance.

This lifting of header 43 is exerted, regardless of possible steam pressure, as the force is transmitted to stud 104 and its companion on the other side regardless of the position of these studs in their slots. Whenever the piece 20 is tripped, the burner or other appliance is shut down and cannot again be started until piece 20 and angle 23 are reset by turning button 27 clockwise which causes piece 20 to ride upon the lug 22 of arm 23'. This prevents another of the dangers found in ordinary boiler controls; namely, when a low-water cut-off of the float valve type is used, and the water in the boiler reaches the cut-off point during operation of the burner, the returning condensation water in a steam system raises the water level sufficiently to raise the float, which starts the burner again, which is quickly stopped when the returned water has again vaporized. These frequent stoppings and startings, when the water level is low, seriously overheat the boiler and can cause damage thereto. In my invention, not only is this prevented, but the burner cannot be restarted without first bringing the boiler water up to its proper level, as the upraised header 43 prevents the upper arm 23' and its lug 22 from taking the normal position.

To cut off steam, upon its excessive rise of pressure, it expands bellows 41 and 42, thereby forcing chamber 43 leftwardly upon its trunnions 104, along slots in the ends of bars 46, 46', until said chamber strikes button 106 on lever 23, pivoted upon shaft 27, thus again releasing member 20 from lug 22, allowing the mercury switch 19 to fall and again cut off the heating element.

Of course it will be understood that various modifications may be made in the construction and arrangement of parts without departing from the spirit of the invention as claimed.

I claim:

1. A device of the character described comprising a chamber, means for supporting said chamber in communication with a boiler for movement in one direction in response to variation in steam pressure in said boiler and means for effecting movement of said chamber in another direction relative to said supporting means in response to variation in water level in said boiler.

2. A device of the character described comprising a chamber, means for supporting said chamber in communication with a boiler for movement

horizontally in response to variation in steam pressure in said boiler and means for effecting vertical movement of said chamber in response to variation in water level in said boiler.

- 5 3. A device of the character described comprising a substantially horizontal frame pivoted at one end, a chamber slidably connected to the other end of said frame for horizontal movement, means opposing movement of said chamber relative to said frame and tending to rotate said frame to move said chamber upwardly, and tubular expandible means for providing communication between said chamber and a boiler whereby said chamber moves horizontally in response to variation in steam pressure in said boiler and vertical-

ly in response to variation in water level in said boiler.

4. A device of the character described comprising a chamber, means supporting said chamber for both horizontal and vertical movement, means opposing movement of said chamber horizontally from a given position and tending to move said chamber upwardly from such position, and tubular expandible means for connecting said chamber to a boiler whereby said chamber moves horizontally in response to variation in steam pressure in said boiler and vertically in response to variation in water level in said boiler.
